UNITED STATES PATENT OFFICE.

FRANK KRUCHOSKI, OF CHISHOLM, MINNESOTA.

NON-REFILLABLE BOTTLE.

1,195,031.

Specification of Letters Patent. Patented Aug. 15, 1916.

Application filed August 4, 1915. Serial No. 43,644.

To all whom it may concern:

Be it known that I, FRANK KRUCHOSKI, a citizen of the United States, residing at Chisholm, in the county of St. Louis and State of Minnesota, have invented new and useful Improvements in Non-Refillable Bottles, of which the following is a specification.

This invention comprehends the provision of a bottle of novel construction with a view 10 of preventing the same from being refilled after the original contents of the bottle have been removed.

The nature of the invention will be better understood from the following description 15 wherein the construction, and arrangement of parts are fully set forth in detail and clearly defined in the appended claim.

In the drawing forming part of this specification like numerals of reference indicate similar parts in the several views and 20 wherein:—

Figure 1 is a vertical sectional view through the bottle constructed in accordance with my invention. Fig. 2 is a transverse sectional view taken on line 2—2 of 25 Fig. 1.

The size, form and material from which the bottle is constructed are immaterial features of the invention, and may be taken 30 care of consistently with the use for which the bottle is intended.

The invention therefore essentially consists of a bottle 5 or other suitable receptacle having a relatively short reduced neck portion 6, and a relatively long and large neck 7 surrounding the neck 6 in spaced relation thereto and defining a pocket 8 by the intervening space between the said necks. The larger neck 7 may constitute a separate element which may be secured in any suitable manner to the bottle 5 at its point of junction with the reduced neck 6, or it may form 40 an integral part of the bottle. The short neck 6 is closed at its upper end as at 9, except for the filling opening 10 disposed in axial alinement with the neck, the latter terminating at its upper end to provide oppositely disposed discharge branches 11 which are curved outwardly and downwardly as 45 shown opening into the pocket 8 an appreciable distance below the filling opening 10. Subsequent to the filling of the bottle through the opening 10, the latter may be

effectively sealed, hermetically, or by cementing therein a ground glass stopper 12, 55 or in any other suitable manner. As shown of course the neck 7 projects an appreciable distance above the short neck 6 and is adapted to receive a cork of ordinary construction. When it is desired to remove the 60 contents from the bottle the latter is turned upside down, and it will be manifest that the liquid will flow through the discharge branches 11 into the pocket 8 and subsequently pass out through the longer neck 7. 65 It will be further noted that by reason of the fact that the filling opening is now sealed, the bottle cannot possibly be refilled, owing to the disposition of the discharge branches 11, and their cross sectional area which is 70 very small, yet sufficiently large to permit a rapid flow of the liquid from the bottle, and finally the air pressure within the bottle preventing any liquid from entering the same through the discharge branches 11. 75

It is believed that from the foregoing description the nature and advantages of the invention will be thoroughly understood without requiring a more extended explanation and therefore the same has been 80 omitted. However I desire to have it understood that I do not limit myself to the precise construction and arrangement of parts herein illustrated and described, and that various changes in this respect may be 85 resorted to when desired as fall within the scope of the appended claim.

What is claimed is:—

A bottle including a long neck, a relatively short neck disposed within the long 90 neck in spaced relation thereto, an overhanging substantially semicircular outlet branch formed on said short neck, the free ends of said branch being disposed in the space between the said necks, said branch 95 having a central opening disposed in alinement with the bore of said short neck and through which the bottle is initially filled, and means for sealing said opening subsequent to the filling of said bottle. 100

In testimony whereof I affix my signature in presence of two witnesses.

FRANK KRUCHOSKI.
